UNITED STATES PATENT OFFICE.

CHARLES F. MCKAY, OF PHILADELPHIA, PENNSYLVANIA.

COMBINED SAFETY VALVE AND GAUGE.

Application filed August 30, 1923. Serial No. 660,080.

In carrying out the present invention it is my purpose to provide a highly simplified and novel form of combined safety valve and gauge that is adapted to be carried by the end of a compressed air line or the end of the usual flexible hose of a hand pump for attachment to the usual valve stems of tires whereby the same may be inflated without any liability of the same blowing out upon over-inflation.

The primary object of this invention resides in the provision of such a device that includes a novel means for adjusting the tension upon the blow-off valve wherein this valve will be unseated whenever the pressure has reached a predetermined degree.

A still further object of my invention is to provide such a device wherein the same may be set for inflating the tire to any pressure desired wherein the liability of the tire being inflated to a degree higher than that set is substantially negligible.

Yet another object is the provision of such a device that is extremely simple of construction and one that may be manufactured and marketed at relatively small cost.

With the above and other objects in view as the nature of the invention is better understood, the same comprises the novel form, combination and arrangement of parts set forth in the following specification, shown in the accompanying drawing and claimed.

In the drawing wherein like reference characters indicate corresponding parts throughout the several views,

Figure 1 is an elevational view of one side of my improved combined safety valve and gauge,

Figure 2 is a detail vertical cross section thereof,

Figure 3 is a longitudinal section taken substantially upon the line 3-3 of Figure 1,

Figure 4 is a cross section through the valve tension adjusting means per se, and

Figure 5 is a bottom plan view of the valve element per se.

Now having particular reference to the drawing, my novel combined safety valve and gauge includes a cylinder 5, and an air inlet tube 6 joined together at their lower ends and having communication with each

other through the medium of a curved by-pass 7, the end of this by-pass connecting with said cylinder 5 being so formed as to provide a valve seat 8, Figure 2. The upper end of the air inlet tube 6 is reduced and externally screw-threaded at 9, whereby the device may be connected to the end of the usual compressed air line or the end of the usual flexible air tube of the hand pump.

Normally resting upon the before mentioned valve seat 8 is a valve element 10 that includes a disc 11 formed upon its under side with a pendant head 12 the edges of which are beveled as more clearly shown in Figures 5 and 6 for positioning within the valve seat, this disc 11 being provided at its periphery and at spaced points thereon with laterally extending lugs 13 that afford a means for spacing said disc from the interior of the cylinder 5 and for allowing the air to pass upwardly between this disc and said cylinder when the valve is raised. Upon the top side of this valve 10 there is formed an upwardly extending pin 14 that is surrounded by the lower end of an expandable helical spring 15 that serves as a means for normally maintaining said valve in position upon the seat 8.

The upper end of this cylinder 5 is open and internally screw-threaded for receiving a disc 16 that is provided with a central screw-threaded passage in which is arranged a relatively elongated thumb screw 17, the lower end of this thumb screw being swivelly connected to a disc 18 that has sliding movement within the cylinder and contacts with the upper end of said spring 15, it being at once apparent that a turning movement of the screw 17 in opposite direction will manifestly cause the tensioning or untensioning of said spring 15 as the case may be. As more clearly shown in Figure 4 this disc 18 is formed on its periphery with a laterally extending pin 19 that has free sliding movement within a vertical slot 20 of said cylinder 5, the wall of this cylinder 5 at opposite sides of this slot being provided with pressure indicating numerals 21, Figure 1.

The connecting by-pass 7 is provided with an outlet nipple 22 upon the end of which is arranged a coupling 23 whereby the device may be attached to the valve

stem of a tire or other article to be inflated and in view of the above description it will at once be apparent that after my device has been attached to the end of an air line, 5 the thumb screw 17 may be adjusted to apply the proper tension to the spring 15 for preventing the valve 10 from opening until the predetermined pressure has been injected into the tire. If the thumb screw 17 has 10 been so turned as to force the disc 18 downwardly into the cylinder for registering the pin 19 with the indicating numeral 60 it will of course be understood that when the device is connected to a tire valve, air will 15 enter the tire until the same has reached a pressure of 60° after which the pressure will be sufficient to raise the valve stem from its seat and allow the air to escape outwardly through the slot 20 and thereby prevent 20 over-inflation of the tire.

It will thus be seen that I have provided a highly novel and simplified form of combined safety valve and gauge, and one that will meet with all of the requirements for 25 a successful commercial use.

Minor changes may be made within the invention without departing from the spirit and scope of the appended claim.

Having thus described my invention,

what I claim as new and desire to secure 30 by Letters Patent is:—

A new article of manufacture constituting an element of a gauge assembly; a one-piece U-shaped casting, one branch of which is adapted to function as a valve cylinder, 35 the wall of said branch being comparatively thin and provided with a slot, the free open end thereof being screw threaded internally for application of a closing disc, the remaining branch being of a greater 40 length and of a comparatively smaller cross sectional diameter and provided at its open end with a reduced screw threaded hose connection, the bight portion embodying a comparatively thick wall forming a valve 45 seat at its point of juncture with the first named branch, said branches and bight portion being of tubular cross-sections, and the second named branch and bight portion forming an air passage, said passage being 50 of substantially uniform diameter from end to end, and said bight portion being provided with a laterally projecting flanged air discharge nipple adapted to be connected with a tire valve.

In testimony whereof I affix my signature.

CHARLES F. MCKAY.
